G. J. GIANNACOPOULOS.
BRIDGING DEVICE FOR RAILWAY CROSSINGS.
APPLICATION FILED DEC. 23, 1921.

1,418,559.

Patented June 6, 1922.

Inventor,

George J. Giannacopoulos

By G. N. Stavler, Atty.

UNITED STATES PATENT OFFICE.

GEORGE J. GIANNACOPOULOS, OF PITTSBURGH, PENNSYLVANIA.

BRIDGING DEVICE FOR RAILWAY CROSSINGS.

1,418,559.

Specification of Letters Patent. Patented June 6, 1922.

Application filed December 23, 1921. Serial No. 524,382.

To all whom it may concern:

Be it known that I, GEORGE J. GIANNACOPOULOS, a citizen of the United States, residing at Pittsburgh, in the county of Allegheny and State of Pennsylvania, have invented certain new and useful Improvements in Bridging Devices for Railway Crossings, of which the following is a specification.

10 This invention relates to car-actuated bridging devices for railway crossings of the general class set forth in my Patent No. 1,259,729, March 19, 1918.

15 The object of the invention is to provide a very simple, durable, relatively inexpensive, and compact device of this character which embodies improvements whereby various details of the construction set forth in my aforesaid patent are completely eliminated and an efficient and positively acting device of this character is provided.

20 My present invention embodies a slidable abutment, adapted to be depressed by the car wheel, a slidable bridging member positioned to serve as a continuation of the abutment when said bridging member is elevated on the depression of the abutment, an intermediate slide whereby motion is transmitted from the abutment to the bridging member, 25 and slidable co-acting parts on the aforesaid member, as also an improved locking means, spring actuating devices, and other improvements set forth more fully hereinafter.

30 35 When my present invention is installed at a railway crossing, car wheels pass over the crossing with minimum noise, shock, or jar and when the crossing has been passed, the abutment resumes its normal, elevated, 40 position, and the bridging member its normal, depressed position so that the crossing arrangement remains as it was before the car passed over.

I am aware that modifications may be 45 resorted to without departing from the essential principles involved in the invention and the particular embodiment of the invention hereinafter described and which is shown in the accompanying drawings is to 50 be considered as illustrative, instead of restrictive, of the scope of the invention.

In the accompanying drawings:

Figure 1 is a plan view showing two of the rails at a railway crossing;

55 Fig. 2 is a side elevation partly in section, the cover being removed; and

Fig. 3 is a vertical section taken through the abutment and the transmitting slide.

The ends of one rail of a crossing are shown at 1 and those of the other part at 2. At each of the four points where the rails cross, at a crossing, there will be provided an embodiment of the invention hereinafter described so that the rail ends will be bridged regardless of which track is used.

Suitable castings may be used for housing the movable parts of the invention, or the rail ends themselves may be provided with the attachments representing the present improvements.

Whichever arrangement is provided, the depressible abutment, the upwardly movable bridging member, and the intermediate transmitting member are mounted in suitable guideways 3 which are provided in the casing or housing 4.

The depressible abutment 5 is provided with a bevel 6 so that the car wheel can readily depress the abutment without shock. 80 The upper face of the abutment on which the wheel travels is shown at 7. A part of one of the guides 3 is formed as an overlapping tongue 8 which is received in a groove 9 in the side of the abutment.

85 The bridging device or slide 10 is of the same thickness as the abutment 5 and disposed so that as the abutment is depressed, the bridging device or slide 10 will rise and its upper face 11 will form a continuation of the upper face 7 of the abutment and will remain in this position to enable the car wheels to cross over the groove in the other rail, with minimum noise, shock and jar.

90 A suitable coil spring 12 disposed in an opening 13 in the abutment 5 and bearing on a lug on the housing 4, keeps the abutment 5 in normal elevated position.

95 A coil spring 14 located in the open portion 15 of the bridging slide 10 and bearing on a lug on the casing 4 presses the bridging device normally downwardly so that it is depressed below the groove in the rail.

To transmit motion from the abutment 5 to the bridging slide 10 there is provided a transmitting slide 16 which is normally pressed toward the abutment 5 by a coil spring 17 located in an opening 18 in said slide. The slide 16 is arranged at right angles to the abutment 5 and it has a bevel face 19 adapted to cooperate with a bevel face 20

on the abutment 5 so that when the abutment is depressed, the engagement of the faces 19 and 20 will result in the transmitting slide moving for the purpose of elevating the bridging slide 10.

The bridging slide 10 has an incline face 21 which bears against a corresponding face 22 on the slide 16. Therefore, when the slide 16 is moved by the depression of the abutment 5, the cooperation of the faces 21, 22, results in the elevation of the bridging device 10 as heretofore explained.

It is desirable to lock the bridging device 10 in elevated position and for that purpose there is provided a spring actuated locking bolt 23 which is adapted to be received in a pocket or keeper 24 in the face 22 when the slide 10 has been properly elevated. The spring 25 which acts on the bolt 23 tends to retract the bolt. An inclined surface 26 on one of the guides 3, or on any part of the housing 4, bears on the end of the bolt 23 and causes it to be forced into the pocket or keeper 24 when the slide 10 is in elevated position.

When the car has completely passed, the springs 12, 14, 15 and 25 restore the parts to normal position.

I claim:

30. 1. In a bridging device for railway crossings, the combination with a depressible abutment, of a bridging device, a transmitting slide actuated on the depression of the abutment and adapted for elevating the

bridging device, and a spring-actuated locking device for holding the bridging device in elevated position until the car wheel has passed thereover. 35

2. In a bridging device for railway crossings, the combination with a depressible abutment slide having a cam or incline, of spring means for holding said abutment slide normally elevated, a slideable bridging device provided with a cam or incline, spring means for normally holding said bridging device depressed, a transmitting slide having cams or inclines adapted for engagement with the cams or inclines on the abutment slide and bridging device, spring means for actuating said transmitting slide, and a 40 spring-actuated locking device carried by the bridging device and adapted to engage the transmitting slide to lock said bridging device in elevated position until the car wheel has passed over said bridging device. 45

3. In a bridging device for railway crossings, the combination with a bridging slide, of a car actuated member adapted to elevate said bridging slide, a spring-actuated bolt carried by the bridging slide and adapted to 50 engage said car member to lock the bridging slide in elevated position, and means for actuating said bolt in opposition to the action of the spring thereof, the bolt being normally retracted when the bridging slide is 55 depressed.

In testimony whereof I affix my signature.

GEORGE J. GIANNACOPOULOS.
